ENVELOPE

Lester R. Snow, Winchester, Mass.

Application December 6, 1935, Serial No. 53,181

2 Claims. (Cl. 229—85)

This invention relates to envelopes and particularly to envelopes containing letters and the like intended to be sealed and sent through the mail.

The object of the present invention is to provide an envelope which upon delivery may be quickly opened without using any tool for that purpose and without tearing or injuring the enclosure.

10 This object is attained by the construction of the envelopes in the manner illustrated in the accompanying drawing.

For the purpose of illustrating the invention one preferred form and two modified forms are illustrated in the drawing, these forms having been found to give satisfactory results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawing

25 Figure 1 represents a front elevation of an envelope embodying the principles of the present invention.

Figure 2 represents a rear elevation of the same.

Figure 3 represents a longitudinal vertical section of same.

30 Figure 4 represents a front elevation of a modified form of said envelope, a portion of one corner being in section.

Figure 5 represents a rear elevation of same, partly in section, and

35 Figure 6 represents a rear elevation of another modified form of envelope.

Similar characters indicate like parts throughout the several figures of the drawing.

40 In the drawing, 10 is an envelope having side flaps 11, 11x, over which extends a lower flap 12 secured to the side flaps 11, 11x in the usual manner.

The upper end of the envelope has a closing flap 13 which extends over the lower flap 12 and is adapted to be secured thereto.

45 The fold of the flap 11 is at right angles to the upper and lower edges of the envelope 10.

The fold of the side flap 11x is out of parallelism with the fold of the side flap 11 and extends at an angle from the top of the envelope 10 to the bottom thereof.

50 By making the envelope in this manner one end has a right-angled triangular extension 14. From the point 15 where the folds of flaps 13

and 11x meet, the end of the envelope 10 is provided with a plurality of aligned perforations 16, which line of perforations is parallel to the fold of the end flap 11.

The envelope 10 is adapted to receive an enclosure 17 which contacts with the upper end of the fold of end flap 11x at 15, and is thus prevented from moving endwise of said envelope.

Obviously, therefore, the enclosure 17 when inserted into the envelope cannot enter the triangular extension 14.

The line of perforations 16 in the envelope 10 is at the edge of the enclosure 17 or immediately beyond the same.

Consequently, when the envelope 10 contains the enclosure 17 with the flap 13 sealed and it is desired to open the same, a person may grasp the lower end of the extension 14 at 15x and separate this extension 14 from the body of the envelope along the line of perforations 16.

By doing this no envelope opener, knife or other tool is required to open the envelope and the extension 14 may be quickly removed without any danger of tearing or injuring any portion of the enclosure.

25 This is of considerable advantage as heretofore in opening envelopes the enclosure is very liable to be torn or otherwise injured in the opening operation.

30 The inclined fold of the end flap 11x may be inclined downwardly and outwardly from the upper edge of the envelope as shown in Figs. 1, 2 and 3, or it may be inclined upwardly and outwardly from the lower edge as shown in Figs. 4 and 5.

35 In Figs. 4 and 5 a modified form of envelope is shown in which the extension 18 beyond the line of perforations 16 has a portion thereof parallel to the edge of the fold 11 at the opposite end of the envelope while another portion 40 is inclined as at 19.

45 In this construction the inclined portion has a flap 20 which is secured to the end flap 11x, as shown in said Figs. 4 and 5.

This form of envelope has some advantages as portions of the edges of both end flaps are parallel, thus making the envelope more convenient for stacking and filing away in boxes or in a chute of a stamp cancelling machine.

50 Another modified form of envelope is shown in Fig. 6 in which one end of the envelope has the end flap 11 folded over with its edge perpendicular to the longitudinal upper and lower edges of said envelope, while the opposite end has two flaps 21 and 22 which are each folded over on 55

lines 23 and 24 at an angle to each other and extending inwardly meeting at the point 25.

The enclosure of this envelope would be prevented from moving into the triangular extensions 5 26 and 27 by coming into contact with the folded edges 23, 24 at 25.

In this form of envelope it would be necessary in order to open the envelope to tear off the extensions 26 and 27 by two operations, one from the top of the envelope and the other from the 10 bottom of the envelope.

In the form of envelope shown in Figs. 1, 2 and 3 the tearing off of the extension 14 would be started from the bottom of the envelope, while in the form shown in Figs. 4 and 5, the tearing off of the extension 18 would be started from the top 15 of the envelope.

The prime object of the invention is to provide means whereby the enclosure 17 will always be retained against the end 11 leaving extensions 14, 18 or 26, 27 at the opposite end of the envelope containing no part of the enclosure and having lines of perforations 16 extending from the top to the bottom of the envelope whereby these extensions may be quickly torn off, giving access to and permitting the removal of the enclosure 17.

The envelope in either one of these forms may be made cheaply and possesses advantages which are not found in envelopes now in general use.

30 Envelopes have been made, however, with a line of perforations at one end of the envelope parallel with an edge thereof which may be torn off to give access to the enclosure but as far as is known none of these envelopes are provided with means for retaining the enclosure between this line of perforations and the opposite end of the envelope.

Consequently, when an envelope of this character is used and the end torn off along the line of perforations, there is great liability of tearing off portions of the enclosure which obviously is a great disadvantage.

5 This objection is overcome in the envelope constructed in accordance with the present invention.

It is believed that the operation and many advantages of the invention will be understood 10 without further description.

Having thus described my invention, I claim

1. An envelope having at one end a right-angled triangular extension having an outer fold at its hypotenuse, the front and rear walls of said extension being disconnected except at said outer fold, said extension having a short horizontal side at one end and being separable from the body of the envelope along a line of perforations perpendicular to a longitudinal edge of the envelope and extending through the front and rear walls thereof from the juncture of said angular fold and said longitudinal edge.

2. An envelope provided with end flaps extending toward each other and nearly to the center 25 of the envelope, one of which is folded at an angle to the fold of the other at the opposite end of the envelope to form a right angled extension the shortest side of which is aligned with a longitudinal edge of the envelope, said envelope having a line 30 of perforations extending from top to bottom thereof and parallel to said opposite end and is provided with a bottom flap folded over and secured at its upper edge to both of said end flaps.
